UNITED STATES PATENT OFFICE.

JAMES A. HALE AND WILLIAM R. RAMSEY, OF BALTIMORE, MARYLAND.

REFRIGERATOR.

SPECIFICATION forming part of Letters Patent No. 225,595, dated March 16, 1880.

Application filed January 2, 1880.

To all whom it may concern:

Be it known that we, JAMES A. HALE and WILLIAM R. RAMSEY, both of Baltimore city, State of Maryland, have invented certain new and useful Improvements in Refrigerators; and we hereby declare the same to be fully, clearly, and exactly described as follows, reference being had to the accompanying drawings, in which—

10 Figure 1 is a vertical sectional view of our refrigerator on line y y , Fig. 2. Fig. 2 is a horizontal sectional view on the line x x , Fig. 1. Our invention relates to that general class of household-refrigerators having an ice-box located in the upper part of the same, the interior of the refrigerator being cooled by the natural convective currents of air passing through the ice-box, and thence through the refrigerating-chamber; and it consists, mainly, 15 in the arrangement of the interior of the refrigerator, the object being to secure the maximum refrigerating-space compatible with an adequate ice-box, water-cooler or drip-pan, and air-chutes, and to so arrange these adjuncts as not to impede the placing within or removal from the refrigerator of articles of food, &c., and incidentally to afford facility for cleaning the interior of the refrigerator.

In the accompanying drawings, A A' are 20 the usual inner and outer walls of the casing, having a suitable filling, such as sawdust or equivalent material, interposed, if desired; or the space between the walls may be, and by preference is, left empty.

25 B is the ice-box, occupying the front upper portion of the refrigerator, and having side walls, b b, near the inner walls of the same, leaving air spaces or chutes I I between, as shown.

30 On ledges b' b' in the ice-box rests the floor E, which consists of perforated sheet metal, corrugated, as shown, and provided with gutters f f, leading from front to rear of the refrigerator. The floor E has a slight downward pitch to the rear. Above it is a grating, G, provided with transverse strips g g, upon which the ice rests.

Beneath the floor E are a number of ledges inclined laterally, and having, also, a downward and rearward pitch. At their lower ends these ledges have upturned flanges e', and

the upper end of each ledge extends some distance over the flange e' of the next to the left. These upper edges are so located as to come beneath those portions of the corrugated floor 55 E next adjoining the gutters f, and void of perforations, so that by no possibility can the drip fall on the edges of the ledges and run along their under side into the preserving-chamber D.

Against the rear wall of the refrigerator, and at a point just beneath the ledges e, is secured the drip-receptacle or water-cooler C, which is enameled on the inside, and has a pipe and faucet, c, as shown.

In operation, ice being laid on the grating G, the adjacent air is cooled thereby, and descends through the perforations in the floor E, between the ledges e, and into the main chamber D. The warmer air thereby displaced rises through the chutes I, and in its turn descends through the ice, the directions of the currents being shown by the arrows.

Experience has demonstrated that descending air-chutes are neither necessary nor desirable, except, perhaps, in refrigerating butchers' stalls or other refrigerators which require to be frequently opened. These descending chutes produce such a rapid circulation in the refrigerator as to result in a great waste of ice. 75

In that class of refrigerators which, like our own, dispense with the descending air-chute, the ice has heretofore been laid on gratings and the air passed through it and out at the bottom; but the difficulty was met, that the 80 air would seek the freest channel and the ice would melt unequally. This evil we obviate by means of the perforated partition or floor E, which will not admit of the passage of a determined current of air through any part of the ice-chamber, but effects an equalization of the descending currents, resulting in a uniform melting of the ice and producing a practically uniform temperature throughout the device. The arrangement of the parts is, moreover, such as to economize space and facilitate the charging of the ice-box, and the air-chutes I I occupy a space which could not conveniently be utilized as a part of the storage-chamber or for any other purpose.

The drip-receptacle C is located at the back of the refrigerator, where packing or storage

- space is less in demand than at the front, and access may be had to it through the ice-chamber, so that the cold water therein contained may be used for cooling bottled or hermetically-sealed goods. As the air, in circulating, passes directly in contact with the ice in passing through the ice-chamber, it parts with its moisture, maintaining a perfectly dry atmosphere within the preserving-chamber.
10. What we claim as new, and desire to secure by Letters Patent, is—
1. The combination, in a refrigerator, of an open-bottomed ice-box having inclined and

rearwardly-pitched slats, a corrugated perforated partition, and a drip-receptacle, as set forth.

2. In combination with the ice-box having grating, and corrugated, guttered, and perforated partition, the inclined slats *e*, whose upper edges underlie an imperforate part of the said partition, as set forth.

JAS. A. HALE.
WM. R. RAMSEY.
